UNITED STATES PATENT OFFICE.

SAMUEL C. McKEOWN, OF EAST ORANGE, NEW JERSEY, ASSIGNOR TO SPLITDORF ELECTRICAL COMPANY, OF NEWARK, NEW JERSEY.

IGNITION SYSTEM.

1,292,838.

Specification of Letters Patent. Patented Jan. 28, 1919.

Application filed January 29, 1918. Serial No. 214,324.

To all whom it may concern:

Be it known that I, SAMUEL C. McKEOWN, a citizen of the United States, residing at East Orange, in the county of Essex and State of New Jersey, have invented certain new and useful Improvements in Ignition Systems, of which the following is a specification.

My invention relates to an ignition system such as used for the purpose of firing the charges in an internal combustion engine.

Within the last few years the rotative speed of the crank shaft has been materially increased so that considerable trouble has been experienced in producing ignition apparatus which will satisfactorily fire these high speed engines and which will have a reasonable length of life, since in general it follows that the higher the speed the greater the wear on operating parts. In a four cylinder four cycle engine 100 sparks per second are required when the engine is turning over at 3000 revolutions per minute, hence it is seen that the breaker mechanism which is used to control the sparks must function with exceeding rapidity and precision and in order to withstand the wear occasioned by such speeds as the above and even lower speeds, special means must be provided and great care exercised in the construction of the parts.

If a high tension magneto be used for ignition purposes the cam which operates the circuit breaker should, to get the greatest effect from the coil windings, hold the breaker contacts open as long as possible in order to give the coil an opportunity to expend its energy across the spark gap in the engine cylinders to which it is then connected. It is usual to provide means for advancing and retarding the time of spark with reference to the engine pistons and in some cases where this range of advance and retard is considerable a condition may be obtained in the full retard position such that the distributor member may have passed beyond the line of contact in the distributor block while the current is still flowing through the secondary winding of the induction coil, which may be on the armature of the magneto or elsewhere, under which condition burning of the insulating material will ensue in the neighborhood of

the distributor contact. In addition to this difficulty the spark may jump from the distributing member to another distributor contact in the direction of rotation of the distributing member with consequent detrimental results which will be at once obvious. This latter trouble is apt to be encountered in a distributor that is relatively small in design, necessitated by certain conditions of mounting on the engine, and where a wiping contact brush is used. Such brushes are usually of carbon and many times leave a thin track of carbon dust around the distributor from contact to contact and if the spark is maintained too long on the cylinder under compression, it may change its direction over the carbon trail to another cylinder where there is no compression and little resistance to its passage.

It is the primary object of my invention to provide an ignition system in which the above difficulties are overcome and in which the life of the operating parts are materially increased.

Other and further objects will be apparent to those skilled in the art after a study of the specification taken in connection with the drawings which form a part of this specification.

In the drawings, Figure 1 illustrates a magneto particularly adapted for firing a two cylinder internal combustion engine, further reference to the details of which may be found in Patent #1,189,374, issued July 4, 1916, to Charles T. Mason.

Fig. 2 illustrates one position of the main and auxiliary circuit breakers used in my invention.

Fig. 3 shows diagrammatically the position of the distributor parts corresponding to the position of the circuit breaker in Fig. 2, both being used in connection with the machine shown in Fig. 1.

Figs. 4 and 5 illustrate another position of the distributor parts and circuit breaker from those shown in Figs. 3 and 2.

Fig. 6 shows the distributor turned 180 degrees from Fig. 4 in which the cam of Fig. 5 would be turned 180 degrees correspondingly.

Figs. 7 and 8 illustrate the position of the distributing parts and circuit breaker mechanism at another position of operation, while

Fig. 9 illustrates the distributor parts turned through 180 degrees from that of Fig. 7.

In Figs. 1 to 9 inclusive the breaker mechanism is indicated as fixed, that is, there is no advance or retard shown on the breaker mechanism.

Fig. 10 illustrates diagrammatically a four cylinder distributor in operative relationship with the breaker mechanism shown in full advance position.

Fig. 11 shows the breaker mechanism in full advance position but the cam in slightly different relation.

Fig. 12 indicates the distributor parts in operative relation with the breaker mechanism in full retarded position.

Referring now to the details, 1 is a magneto of the type hereinabove referred to having a distributing member 2 operatively connected with the shaft 3. Distributor contacts 4 and 5 collect the current from distributor 2 and deliver it by means of conductors 6 and 7 to their respective spark plugs in the engine cylinders. Mounted on the opposite end of the magneto and consequently not shown in Fig. 1 is a circuit breaker mechanism shown somewhat diagrammatically in Fig. 2. This breaker mechanism has a stationary contact member 8 carrying an adjustable contact 9. A movable member 10 carries a contact 11 adapted to cooperate with the contact 9. The member 10 is preferably pivoted, as by means of a pivot screw 12, to the frame of the breaker box, a spring 13 being used to return the breaker to close the contacts 9 and 11 after the same have been separated by the cam 14. In order to produce a relatively long life of the cam 14 and bumper 15, carried by the movable member 10, the cam lobes 16 and 17 are made relatively long and flat. If these lobes are made very sharp experience has shown that they would cut the bumper 15 away rapidly, however, where the lobes 16 and 17 are made relatively long and flat difficulty is encountered by the distributor member 2 turning forward in its rotative movement to such a point that the brush 18, referring to Fig. 4, leaves the end 19 of the distributing member 2 before the breaker arm 10 has closed the contacts 9 and 11 which, as shown in Fig. 5, control the circuit through the primary P of the induction coil, whose secondary S is connected to the brush 18 or the additional difficulty may be encountered of the point 20 of the distributing member 2 advancing so near the contact 5 that the spark will jump from the end 20 to the contact 5 prematurely. This latter trouble is further aggravated by the track of the brushes on that part of the surface between the ends 19 and 20, which is of insulating material. As shown in Fig. 5 the cam 14 has just separated the contacts 9 and 11 and the current from

the secondary S is passing to distributor contact 4. It will be seen that the cam lobe 17 (in Fig. 4) will still be in engagement with the bumper 15 after the brush 18 has left the end 19 of the distributing member 2 70 and burning of the insulation would follow or the spark might jump from the end 20 to the distributor contact 5 as already pointed out, if means were not provided to prevent this. I provide such means which 75 are as follows:—Mounted on the stationary contact 8, which is preferably insulated from the breaker box, is a flexible member 21 carrying a bumper 22 and contact 23 which is adapted to coöperate with a stationary contact 24 which, as diagrammatically shown, is connected to the framework of the breaker box which is usually designated as "ground". Referring again to Figs. 4 and 5 it will be seen that the lobe 16 of cam 14 is just coming 80 into engagement with the bumper 22 and directly thereafter the member 21 is moved to close the contacts 23 and 24 before the brush 18 leaves the end 19 of distributor member 2. Closing of the contacts 23 and 24, as above 85 described, closes the primary circuit of the induction coil and thereby suppresses the action of the secondary across the spark gap so that the troubles as hereinbefore outlined are removed. When the distributing member 90 2 has turned 180 degrees from that shown in Fig. 4 it will be in the position in Fig. 6. In this position the only difficulty encountered being the tendency of the spark to jump from the point 20 to the contact 4 but 95 the means above described prevents this trouble.

As the cam 14 and the distributing member rotate forward from the positions shown in Figs. 4 and 5 the auxiliary breaker maintains the contacts 23 and 24 closed until the main circuit breaker itself closes the contacts 9 and 11 as shown in Fig. 8, in which position the distributing member 2 is indicated in Fig. 7. From this point on, the circuit 110 breaker arm 10 prevents any action of the primary on the secondary S until the positions of Figs. 2 and 3 are reached when action takes place as already described.

In Fig. 10 I have shown diagrammatically 115 a distributor block 25 having contacts 26—27—28 and 29 coöoperating with which is a distributing member 30. The circuit breaker mechanism associated with the distributor has the same corresponding parts as 120 shown in Figs. 2—5 and 8 although the cam has 4 lobes 31—32—33 and 34. The cam 14 may have any number of lobes required. In Fig. 10 the circuit breaker is indicated in its full advance position under which condition the relation between the distributing member and the distributor contacts of the block 25 are as indicated; that is to say, the distributing member 30 has just come into coöoperating line with the distributor contact 125 130

26. As the cam 14 turns in the direction of the arrow the main circuit breaker contacts 9 and 11 are opened causing the primary P to act on the secondary S in the well known manner and current from the secondary S passes to the distributor contact 26 through the distributing member 30 which has advanced forward but is still in coöperative relationship with the distributor contact 26; hence no trouble will be encountered in full advanced position of the breaker box. However, when the breaker box is retarded as indicated in Fig. 12 the cam, which is synchronously timed with the distributor, all as is well known and understood, must turn in the direction of rotation a number of degrees forward before it comes into engagement with the bumper 15 on the circuit breaker arm 10 and, as indicated in Fig. 12, the contacts 9 and 11 are still separated although they are about to close while it is seen that the distributing member 30 has left the line of coöperation 35 of the distributor contact 26 and arcing would be produced between the distributing member 30 and the contact 26 but it will be noted that the auxiliary breaker member 21 has already closed the contacts 23 and 24 thereby suppressing the current impulses from the secondary winding S.

From what has been said it will be seen that I have aimed to secure long life of the cam and main circuit breaker by constructing these parts so as to give maximum life, yet in so constructing the parts I have encountered certain ignition difficulties which I have overcome by means of an auxiliary circuit breaker which, in my preferred form, is operated by the same cam that operates the main circuit breaker. It is evident that the auxiliary breaker may be operated by some other means and that the relation of the parts of the auxiliary breaker may be reversed in position. It will also be understood that while I have shown a wiping contact in the distributor that my invention is applicable to a distributor having a jump spark, the main function then of the auxiliary breaker being to suppress the spark before the distributor finger or rotating contact turns far enough to permit the spark potential existing to jump the lower resistance gap of an adjacent contact where there is no compression to act against. While I have shown what may be termed a service magneto as the source of current for the induction coil it will be apparent that any other suitable source of energization of the coil may be utilized, for example, a battery and vibrator such as shown in Patent #1,207,193, issued December 5, 1916, to Charles T. Mason may be connected to the contact member 8 for the purpose of producing a starting ignition current; or an auxiliary starting magneto may be con-

nected in the same manner as the battery and vibrator to the contact member 8. When these auxiliary devices are used for starting purposes the tendency is to run into the trouble heretofore pointed out but since either of the arrangements just mentioned are timed by the main breaker arm 10 and further controlled by the auxiliary breaker 21 the difficulty is overcome. Numerous other changes and alterations may be made in the various details necessary to carry my invention into practical operation, and I, therefore, do not wish to be limited to the details herein shown which are more or less diagrammatical in form, and it is intended that the claims shall cover the invention broadly whether or not the current for the induction coil be furnished exclusively by the service magneto itself or whether an auxiliary source be used in connection with the service magneto for the purpose of assisting in starting.

Having thus described my invention what I claim is:—

1. In an ignition system, an induction coil having primary and secondary windings with means for producing current in said primary winding, a distributor having distributor contacts and a distributing member adapted to coöperate with said contacts connected to the secondary winding, a main circuit breaker for controlling the action of the primary winding on the secondary and an auxiliary breaker for limiting the control of the main breaker on the primary for the purpose described.

2. In an ignition system, an induction coil having primary and secondary windings with means for producing current in said primary winding, a distributor having distributor contacts and a distributing member adapted to coöperate with said contacts connected to the secondary winding, a main circuit breaker connected in circuit with said primary winding, a cam adapted to act on said breaker to break the circuit through said primary winding whereby current is generated in said secondary and an auxiliary breaker adapted to be acted on by said cam subsequent to the operation of the main breaker for suppressing the action of the primary on the secondary for the purpose described.

3. In an ignition system, an induction coil having primary and secondary windings with means for producing current in said primary winding, a distributor having distributor contacts and a distributing member adapted to coöperate with said contacts connected to the secondary winding, a movable member carrying a contact, a stationary member carrying a contact adapted to coöperate with the movable contact, said contacts being in said primary circuit, a cam adapted to act on said movable member to

make and break said primary circuit whereby current impulses are generated in said secondary winding, a second stationary contact and a movable contact connected to the 5 first mentioned stationary member adapted to be acted on by said cam and to coöperate with the second mentioned stationary contact to close said primary circuit after having been opened by the first mentioned moving 10 able member for the purpose described.

4. In an ignition system, an induction coil having primary and secondary windings with means for producing current in said primary winding, a distributor having distributor contacts and a distributing member adapted to coöperate with said contacts connected to the secondary winding, a pivoted movable member carrying a contact, a stationary member carrying an adjustable contact adapted to 15 coöperate with the movable contact, said contacts being in said primary circuit, a cam adapted to act on said pivoted member to make and break said primary circuit, whereby current impulses are generated in said 20 secondary winding, a second stationary contact, a flexible member attached to the first mentioned stationary contact carrying a contact adapted to coöperate with the second mentioned stationary contact and further adapted to be acted on by said cam to 25 close after a predetermined interval said primary circuit after it has been opened by said pivoted member, for the purpose described.

5. In an ignition system, an induction coil having primary and secondary windings with means for producing current in said primary winding, a distributor having distributor contacts and a distributing member 30 adapted to coöperate with said contacts connected to the secondary winding, a main circuit breaker for producing action of said primary on said secondary whereby current impulses are sent from said distributing 35 member to said distributor contacts and an auxiliary breaker for suppressing said cur-

rent impulses before said distributing member passes out of the line of coöperation with said distributor contacts.

6. In an ignition system, an induction coil 50 having primary and secondary windings with means for producing current in said primary winding, a distributor having distributor contacts and a distributing member adapted to coöperate with said contacts connected to the secondary winding, a main circuit breaker for producing action of said primary on said secondary whereby current impulses are sent from said distributing member to said distributor contacts, with means 55 for advancing and retarding said action, a bumper on the movable part of said breaker, a cam adapted to engage said bumper said cam and bumper being so arranged with reference to said distributor parts and so constructed for giving maximum life of operation that in full retard position said distributing member will pass from the line of coöperation with an associated distributor contact, and means for suppressing said current impulses before the main circuit breaker 60 closes and the distributing member leaves the line of coöperation of the distributor contact.

7. In an ignition system, an induction coil having primary and secondary windings 75 with means for producing current in said primary winding, a distributor having distributor contacts and a distributing member adapted to coöperate with said contacts connected to the secondary winding, a main circuit breaker for producing action of said primary on said secondary whereby current impulses are sent from said distributing member to said distributor contacts, a cam for operating said breaker and an auxiliary 80 breaker operated by said cam to close the primary circuit before the main circuit breaker closes and before the distributing member leaves its coöperating contact for the purpose described.

In witness whereof, I affix my signature.
SAMUEL C. McKEOWN.
